FABRIC HANGING DEVICE

Jacob Lishman, 75 Middleneck Road, Great Neck, N.Y.
Filed Apr. 6, 1962, Ser. No. 185,714
1 Claim. (Cl. 160—348)

This invention relates to fabric hanging and pleating devices, and particularly to a device for hanging draperies, curtains and other fabrics vertically from a horizontal support.

Draperies may be formed of a variety of materials, ranging from light and flexible plastic sheet materials to heavy, woven fabrics, all of which are referred to herein-after as fabrics. It is highly desirable with all of these fabrics that devices employed to fasten to them, and to hang or suspend them from a horizontal support, not damage them, as will drapery pins and the like.

Furthermore, it is desirable that the hanging device enhance the appearance of the fabric, as by forming pleats in a straight-hanging fabric, or by supporting the fabric firmly along a substantial area at its top so that separate fabric stiffening materials will be unnecessary.

Other desirable characteristics in the fastening and hanging device are that it be easily attachable to and removable from the fabric to permit dismounting of the latter for cleaning and other purposes, that it be useable with any of a large variety of materials having different colors, designs and the like, and that it be economical to produce.

The device of the present invention achieves all of these desirable ends. The device in its broad aspect comprises inner and outer elongated concentric tubular members formed of a material which is stiff and rigid relative to the fabric, the inner member having along a portion of a vertical edge a fixture for attaching it to and suspending or hanging it from a horizontal support. The outer member is slotted along its vertical length, with the slot being of sufficient width to receive a fabric and the hanging fixture of the inner member, so that it may be slid down over the fabric and the inner member when the fabric is placed around the inner member with the fabric and inner member hanging fixture passing through the slot. The diameter of the members is selected to permit them to hold the fabric snugly between them, thereby holding against lateral and vertical movement relative to the device. The outer member also may, if desired, have substantially parallel elements or tabs near its top extending from the slot to hold the fabric away from the tubular members, thereby enhancing the three-dimensional character of the hung fabric.

The tubular construction of the members provides them with rigidity in a vertical direction; this causes vertical stiffening of the fabric at its top, making it unnecessary to use secondary stiffeners in the fabric. The slotted tube construction of the outer member at the same time provides it with clamping strength coupled with resilience, so that it may be positioned easily and will be adaptable to various thicknesses of fabric.

In preferred embodiments of the invention, the device may be fitted near the top with a positive fabric-clamping means which may comprise a simple cap across the top of the outer member, or which may be an element protruding from the inner face of the outer member, against which the top of the inner member will clamp the fabric. The desirability of having such a positive fabric-clamping means will be determined largely by the nature of the fabric. In nearly all cases, the top edge of the fabric is hemmed to avoid a raw edge, so that a seam is provided. With light-weight fabrics, such as stitched plastic shower curtains, the contact of the inner member up under the stitched seam and the spring-like clamping pressure of the outer member will be sufficient to hold

2

the fabric against slippage. With heavy fabrics, however, often more than the mere clamping pressure of the outer member and contact of the top of the inner member with the seam will be required to avoid downward slippage of the fabric, and positive fabric-clamping means will be desirable. Heat-sealed plastic hems also may require a clamping means, since the heat-sealed hem may slide past the top of the inner member.

A preferred, and very simply fabricated construction has as the hanging or suspended fixture, a flat ring having a straight edge integral with a vertical edge of the inner member and having a cut-out center which will fit over the horizontal support. The ring is slotted, preferably in a substantially vertical direction, near its bottom to permit it to be positioned over the support. For ease of positioning and best appearance, the cut-out is no closer than $\frac{1}{4}$ to $\frac{3}{4}$ of an inch from the straight inner edge of the ring.

The invention will now be described more fully with reference to the attached drawings, in which

FIG. 1 is an elevation in perspective showing a drapery fastened and hung with the present device;

FIG. 2 is a perspective view of the inner member;

FIG. 3 is a perspective view of the outer member;

FIG. 4 is a plan view of the device with a fabric in place;

FIG. 5 is a section on the line 5—5 of FIG. 4, showing in section the assembled device and fabric;

FIG. 6 is a section of the top part of an alternative form of the assembled device having fabric in place; and

FIG. 7 is a section of the top of an inner member having another form.

Referring now to the drawings, and particularly to FIG. 1 thereof, the illustrated device of the invention comprises an inner tubular member 10, shown as having wrapped around it a drapery 12, whose upper edge is folded back and seamed along line 14. Suspending and hanging ring 16 is an extension of inner member 10, and is shown in position around support 18.

Outer member 20 is positioned in clamping relationship around inner member 10 and drapery 12, with suspending or hanging ring 16 and drapery 12 passing through a vertical slot in the back of outer member 20. Outer member 20 has a pair of parallel tabs or extensions 22 extending from facing edges near the top of its vertical slot, which hold the drapery away from it. The drapery is pinched together by the slot in member 20, and folds together at 24 below the device, thereby forming a pleat 26.

The slot in outer member 20 is shown in FIGS. 3 and 50 4, as vertical slot 28. In FIG. 2, the construction of inner member 10 is shown, with ring 16 being equipped with a cut-out 30, and a slot 32 for use in opening the ring in positioning it over horizontal support 18.

The relationship of the parts of the device in use are 55 shown in FIGS. 4 and 5. In FIG. 4, drapery 12 is shown clamped between outer member 20 and inner member 10, and extending together with ring 16 through slot 28 in outer member 20. Element 34 of outer member 20 forces drapery 12 over inner member 10, thereby clamping it in place.

FIG. 5 shows a side section view along line 5—5 of FIG. 4, with drapery 12 in place. When outer member 20 has been slid down over drapery 12 and inner member 10, the seam 14 of the drapery abuts against the top 36, of inner member 10; being clamped there by element 34 of outer member 20. This serves as a positive lock against downward slippage of the drapery.

FIG. 6 shows a side sectional view of the top portion of a device of this invention, with the fabric in place, in 70 which the top of outer member 20 is provided with cap 38 for clamping fabric 12 in place. Top 36 of inner member 10 presses fabric 12 up against cap 38, thereby creat-

ing a clamp to hold this fabric against downward slip-page.

In FIG. 7, the top of inner member 10 is shown as having at its top an upended portion 40. This spear-like portion 40 is adapted to fit up under seam 14 of a fabric, thereby clamping it and holding it against downward movement relative to the inner member.

The device is formed of a material which is rigid and stiff relative to the fabric, preferably of a transparent plastic which will not interfere with the appearance of the fabric. However, it may be formed of sheet metal, pressed fiber, wood or the like material of sufficient stiffness to hold the fabric firmly and provide support for suspension. The outer member must be of a thin material so that it will be springy and resilient to provide a clamping pressure, yet will be sufficiently flexible for positioning and removal. In the case of opaque materials, it may be decorated or it may be of a neutral appearance.

The device of this invention affords a firm fastening for a fabric, without puncturing, creasing or otherwise damaging it, even after lengthy and repeated use. It also provides a stiffening action along the top of the fabric, and forms a pleat in the fabric.

The device can be constructed of a transparent material to permit the design of the fabric to show through, or it can be a decorative element itself, as desired. Furthermore, it is easily and economically produced, and can be assembled and disassembled readily by anyone, with no particular skill being required to permit the achievement of a neat and well finished fastening.

It will be apparent that the particular forms of the device shown in the specification can be modified without departing from the scope of the invention, which is defined in the claim.

Pursuant to the requirements of the patent statutes, the principle of this invention has been explained and ex-

emplified in a manner so that it can be readily practiced by those skilled in the art, such exemplification including what is considered to be the best embodiment of the invention. However, it should be clearly understood that, within the scope of the appended claim, the invention may be practiced by those skilled in the art, and having the benefit of this disclosure, otherwise than as specifically described and exemplified herein.

I claim:

- 10 A device for suspending a vertically disposed fabric from a horizontal support and adapted to form a pleat in the fabric, said device comprising inner and outer elongated concentrically disposed tubular members formed of a material which is stiff and rigid relative to said fabric, said inner member having along its vertical edge a fixture for attaching said inner member for suspension from said support, and said inner member being of a diameter to press said fabric snugly between said two members and held it therebetween said outer member being slotted along a vertically extended area from its lower edge upwardly to its top, and said slot being of sufficient width to receive the fabric and to permit said fixture of said inner member to slide vertically in said slot between opposing faces of said fabric when the fabric is positioned between said members and extended through said slot, and said outer member having an element near its top and extending from its inner surface against which the top of the inner member will abut to clamp the fabric.
